UNITED STATES PATENT OFFICE.

FREEMAN CASS, OF BROOKLYN, NEW YORK.

THREAD GUIDE FOR SPINNING MACHINES.

Application filed February 17, 1922. Serial No. 537,219.

To all whom it may concern:

Be it known that I, FREEMAN CASS, a citizen of the United States, and residing at Brooklyn, Kings County, State of New York, have invented certain new and useful Improvements in Thread Guides for Spinning Machines, of which the following is a specification.

In modern textile machinery it is customary to employ thread guides made of porcelain or other vitreous material, these guides being formed with an aperture or eye through which the thread travels. On account of the vibration of the threads, they are apt to become disengaged from the guides. To prevent this, the guides are generally made with one or more small fingers extending into the eye or aperture. These fingers being somewhat slender are apt to become broken and the guides themselves sometimes break causing annoyance and difficulty. This invention has for its object to provide a guide of the kind in question which is simple and strong in construction and in which the parts are so shaped as to prevent disengagement of the thread therefrom.

In the accompanying drawing there is illustrated in elevation and partly in section a thread guide embodying the present invention.

The guide as shown in the drawing comprises a body, generally designated by the numeral 10, which is provided at its lower end with a socket 11 adapted to receive a wire or other supporting device 12, such device being secured in the socket by a plug of shellac or other suitable substance 13. The upper portion of the body 10 is provided with an upper eye 14 and a lower eye 15 which are connected by a channel or passage 16. A slot or passage 17 extends upwardly and inwardly from one side or edge of the body 10 and communicates with the channel 16 between the eyes 14 and 15. For convenience of description, the side of the body 10 containing the inclined slot 17 may be regarded as the front side. It will be seen that the rear wall of the eyes 14 and 15 extend rearwardly of the point at which the channel 16 connects with said eyes, and that the front wall of each of said eyes extends forwardly of such point. In other words, the channel 16 communicates with the eyes 14 and 15 at points intermediate their front and rear walls. The rear wall of the eye 15

is preferably spaced a somewhat greater distance from the rear side of the body 10 than is the rear wall of the eye 14. This tends to prevent breaking of the body of the guide back of the eye 15. The rear wall of the channel 16 is preferably curved forwardly which results in strengthening that part of the body between the eyes 14 and 15. The upper wall 18 of the slot 17 is preferably made substantially straight and the lower wall 19 of this slot curves rearwardly and downwardly. That part of the body between the bottom of the eye 14 and the top wall of the slot 17 forms in effect an upper rearwardly projecting finger designated 20 on the drawing and similarly that portion of the body 10 between the upper wall of the eye 15 and the lower wall of the slot 17 forms a lower rearwardly projecting finger indicated as 21. The rear end of the finger 21 is preferably curved as shown at 22. It will be seen the finger 20 extends rearwardly to a greater extent than the finger 21, the result being that if the thread which normally passes through the eye 14 becomes disengaged therefrom and falls downwardly it will tend to enter the lower eye 15, the curvature of the upper and rear portion of the finger 21 facilitating this action.

The foregoing construction therefore provides a guide in which the parts may be made strong and durable and in which the parts are so arranged as to effectively retain the threads in proper engagement with the guide.

Having thus described the invention what is claimed as new and desired to be secured by Letters Patent is:

1. A thread guide for textile machines comprising a body having an upper eye and a lower eye and a channel extending between the bottom of said upper eye and the top of said lower eye, said channel opening into the bottom of said upper eye and into the top of said lower eye at points intermediate the front and rear walls of said eyes, the rear wall of said channel between its point of communication with said eyes being curved forwardly, said body also having an upwardly inclined slot extending rearwardly from one side thereof and communicating with said channel opposite the curved rear wall thereof, the material of said body between the bottom of said upper eye and the top wall of said slot forming an upper rearwardly projecting finger and the material

between the upper wall of said lower eye and the bottom wall of said slot forming a lower rearwardly projecting finger, the inner end of said upper finger projecting rearwardly 5 to a greater extent than said lower finger, and the rear wall of said lower eye being spaced from the rear wall of the guide a greater distance than the rear wall of said upper eye.

10 2. A thread guide for textile machines comprising a body having an upper eye and a lower eye and a channel extending between the bottom of said upper eye and the top of said lower eye, the rear wall of said channel 15 between its point of communication with said eyes being curved forwardly, said body also having an upwardly inclined slot ex-

tending rearwardly from one side thereof and communicating with said channel opposite the curved rear wall thereof, the material of said body between the bottom of said upper eye and the top wall of said slot forming an upper rearwardly projecting finger and the material between the upper wall of said lower eye and the bottom wall 25 of said slot forming a lower rearwardly projecting finger, and the rear wall of said lower eye being spaced from the rear wall of the guide a greater distance than the rear wall of said upper eye. 30

In testimony whereof I hereunto affix my signature.

FREEMAN CASS.
